UNITED STATES PATENT OFFICE.

ALBERT CHAMPION, OF FLINT, MICHIGAN, ASSIGNOR TO CHAMPION IGNITION COMPANY, OF FLINT, MICHIGAN, A CORPORATION OF MICHIGAN.

SPARK-PLUG.

1,358,828.

Specification of Letters Patent. Patented Nov. 16, 1920.

Application filed February 26, 1920. Serial No. 361,401.

To all whom it may concern:

Be it known that I, ALBERT CHAMPION, a citizen of the United States, and a resident of Flint, county of Genesee, and State of Michigan, have invented certain new and useful Improvements in Spark-Plugs, of which the following is a full, clear, concise, and exact description, such as will enable others skilled in the art to which the invention relates to make and use the same, reference being made therein to the accompanying drawings, which form a part of this specification.

My invention relates to spark plugs designed for use with internal combustion engines to ignite the combustible mixture within the cylinder thereof, and wherein an insulator made of porcelain or equivalent material and which supports a central electrode is secured in place within a hollow external shell or casing which carries the outer electrode of the plug; and the principal object of my invention is to provide an improved spark plug comprising an external metallic shell or casing within which a porcelain insulator is located, and in which plug a better joint is secured between the porcelain or equivalent insulator and the external shell or casing thereof and leakage of gas between the insulator and the shell or casing the more effectively prevented when the plug is in use.

A further object of my invention is to provide an improved spark plug having an insulator secured in place within the metallic shell or casing thereof, and in which the insulator is less likely to become cracked or broken in assembling the plug and securing the insulator in place within the casing than has heretofore commonly been the case.

A further object of my invention is to provide a spark plug of the type above referred to and wherein the tendency of the porcelain or like insulator to rotate within the metallic shell or casing thereof as the plug is assembled will be reduced to a minimum, and in which the insulator will in fact not rotate within the shell or casing as the same is secured in place therein through and by means of the usual gland nut employed in spark plugs for that purpose.

My improved spark plug is illustrated in its preferred form in the drawing accompanying and forming a part of the specification; although it will be appreciated that various changes, variations and modifica-

tions may be made in the particular embodiment of my invention illustrated without departing from the spirit thereof, and that my invention includes all such variations and modifications of the particular embodiment thereof illustrated as come within the scope of the concluding claims wherein the distinguishing features in which my invention consists are particularly pointed out.

Referring now to the drawing:

Figure 1 is a view showing my improved spark plug in side elevation, with certain portions broken away in order to better illustrate the construction and relationship of various of the features thereof.

Fig. 2 is a fragmentary view showing the distinguishing features of my invention upon a considerably larger scale.

Fig. 3 is a view showing the metallic follower which enters into my invention, in perspective.

Fig. 4 is a similar view showing the lower or inner end of the gland nut of my improved spark plug, which engages the upper surface shown of the follower illustrated in Fig. 3.

In the drawing the reference numeral 5 designates the external shell or casing of my improved spark plug, which is made of metal and is threaded at its lower end as shown at 6 in order that the plug may be screwed in an opening provided for it in an internal combustion engine cylinder. This shell or casing is hollow, and the upper portion of the interior thereof is threaded as shown at 7; and an internal annular ledge 8 is provided below said threaded portion and about midway of the length of the interior of the said shell.

Secured in place within the shell or casing is an insulator made, commonly, of porcelain or similar vitreous material, although it may obviously be made of mica or in fact of any suitable material having the requisite insulating qualities. The inner electrode of the plug extends through this insulator and is supported thereby, and said insulator is provided intermediate its length with a downwardly inclined annular peripherally extending lower shoulder 10 which overlies the ledge 8 of the shell or casing and is supported by said ledge when the parts of the plug are assembled. The said insulator is also provided with a second peripherally extending annular upper shoulder 11 which lies adjacent the threads formed within the

interior of the shell or casing adjacent the upper end thereof, said shoulder being upwardly inclined from the periphery of the insulator in the form of my invention illustrated, and curved or concave in form to thereby avoid sharp corners in the insulating member of the plug.

Surrounding the upper end of the insulating member 9 is an annular metallic follower 12 the upper surface of which is flat and lies in a plane extending substantially at right angle to the axis of the plug, and the under side of which follower is inclined in a manner similar to the inclination of the upper shoulder 11 of the insulating member; and the reference numeral 13 designates a gland nut in threaded engagement with the threads provided at the upper end of the casing 5, the inner diameter of the said gland nut being somewhat greater than that of the upwardly extending portion of the insulator so as not to bind therewith as the gland is rotated in assembling the plug to secure the insulator in place within the shell. The lower end of this gland is so shaped as to reduce the area of contact between the said lower end and the upper surface of the follower 12 against which it abuts; the said gland in the form of my invention illustrated being beveled, as shown at 14, to thereby provide a narrow annular extremity 15 which contacts with the upper surface of the follower along and throughout an annular band or zone 16 of small width as compared with the width of the upper surface of the follower, and which zone is located substantially midway between the inner and outer peripheries of the said follower, as illustrated in Fig. 3 of the drawing.

A suitable gasket 17 preferably yielding in character so that it may be compressed is interposed between the lower annular shoulder 10 and the ledge 8, and which gasket is compressed between said members when the gland 13 is screwed downward and into the interior of the plug; and a second yieldable gasket 18 is also preferably provided between the underside of the follower 12 and the upper shoulder 11 of the insulating member 9, and through which last mentioned gasket force is communicated to the insulator as the gland nut is rotated in assembling the plug, as will be appreciated. These gaskets form yieldable packings which prevent the outflow of gas from the interior of the cylinder of the engine, and also prevent the porcelain from being cracked or broken as the gland nut is tightened because of the yieldable and cushioning properties.

The reference numeral 19 designates the outer electrode of the plug which is secured in any suitable way to the lower end of the shell or casing 5, and the reference numeral

20 designates the inner electrode which extends through a passage formed in and is insulated by the insulator 9; these electrodes being so arranged that sparks pass between them when the plug is in use, as will be understood.

In view of the premises it will be appreciated that the force due to the screwing of the gland nut 13 into the hollow shell 5 in assembling the parts of the plug is communicated to the annular follower 12 through a limited area at the extremity of said gland which results from the reduction of the size of the inner end of the said gland, and through the reduced annular band or zone 16 of small width located about midway the width of the upper surface of the said follower, as indicated in Fig. 3, with which the reduced inner end of the gland contacts; and through the said follower to the porcelain insulator which is thus forced downward and against the gasket 17. This localization of the force communicated to the follower from the gland along and throughout a comparatively narrow annular zone reduces the friction between the gland and the follower, and prevents the follower from rotating with the gland and transmitting rotary movement to the insulator as the same is clamped in place within the shell, and provides a construction and arrangement of spark plug in which the tightening of the gland as the plug is assembled will not communicate rotary motion to the insulator; from which it follows that during the securing of the insulator in place within the shell or casing no rotary movement will be communicated to the insulator, and the lower shoulder 10 thereof will not rotate in contact with the gasket 8. A better and a more effective gas tight joint or packing is thus secured at the lower end of the insulator as the yieldable gasket 17 which, upon being compressed, provides such a packing, is in no way torn or injured by rotary movement of the shoulder 10 against the same as the said shoulder is forced against the gasket, as is likely to be the case in spark plugs wherein rotary motion occurs or may occur during the screwing home of the gland whereby the insulator is forced against a ledge within the casing which supports the insulator of the plug and between which and a shoulder of the insulating member a yieldable packing is commonly interposed.

Having thus described and explained my invention, I claim and desire to secure by Letters Patent:

1. In a spark plug of the class described, a hollow metallic shell or casing interiorly threaded at its upper end and having an internal downwardly inclined ledge below said threaded portion; an insulator arranged within said shell and having a lower

- shoulder inclined similarly to and adapted to overlie said ledge, and an upper inclined shoulder adjacent the lower end of the interiorly threaded portion of said shell; an 5 annular metallic follower located within said shell and above the upper of the shoulders of said insulator and the under side of which is inclined similarly to said upper shoulder and the upper surface of which 10 follower is in a plane substantially at right angles to the axis of the plug; an exteriorly threaded gland in threaded engagement with the threaded portion aforesaid of said shell, and the lower end of which gland is 15 reduced in size so as to provide a narrow annular area of contact between said lower end and the upper surface of said follower; and a gasket between the ledge aforesaid and the lower of the shoulders of said insulator. 20
2. In a spark plug of the class described, a hollow metallic shell or casing interiorly threaded at its upper end and having an internal ledge below said threaded portion; an 25 insulator arranged within said shell and having a lower shoulder which overlies said ledge, and an upper shoulder; an annular metallic follower located within said shell and overlying the upper of the shoulders of 30 said insulator, and the upper side of which follower is in a plane substantially at right angles to the axis of the plug; an exteriorly threaded gland in threaded engagement with the threaded portion aforesaid of said shell 35 and the lower end of which is of reduced size and is so disposed as to contact with the upper surface of said follower about midway the width thereof, and throughout an annular band or zone of small width as compared with the width of said follower; and a 40 gasket interposed between the ledge aforesaid and the lower of the shoulders of said insulator.
3. In a spark plug of the class described, 45 a hollow metallic shell or casing interiorly threaded at its upper end and having an internal ledge below said threaded portion; an insulator located within said shell and having a lower shoulder adapted to overlie 50 said ledge, and an upper shoulder adjacent the lower end of the interiorly threaded portion of said shell; an annular metallic follower located within said shell, and above the upper of the shoulders of said insulator; an 55 exteriorly threaded gland in threaded engagement with the threaded portion aforesaid of said shell, and the lower end of which is beveled to provide a narrow annular area of contact between said lower end and the 60 upper surface of said follower; a yieldable gasket between the ledge aforesaid and the lower of the shoulders of said insulator; and a second yieldable gasket between the under side of said follower and the upper 65 of the shoulders of said insulator.
4. In a spark plug of the class described, a hollow metallic shell or casing interiorly threaded at its upper end and having an internal ledge below said threaded portion; an insulator located within said shell and having a lower shoulder adapted to overlie 70 said ledge, and an upper shoulder; an annular metallic follower located within said shell and above the upper of the shoulders of said insulator; an exteriorly threaded 75 gland in threaded engagement with the threaded portion aforesaid and the lower end of which engages the upper surface of said follower; a yieldable gasket between the ledge aforesaid and the lower of the 80 shoulders of said insulator; and a second yieldable gasket between the under side of said follower and the upper of the shoulders of said insulator.
5. In a spark plug of the class described; 85 a hollow metallic shell or casing having a threaded portion adjacent its upper end, and an internal annular ledge below said threaded portion; an insulator located within said shell and having a lower annular 90 shoulder which overlies said ledge, and an upper shoulder; an annular metallic follower located within said shell and overlying the upper of the shoulders of said insulator, and the upper side of which follower 95 is in a plane substantially at right angles to the axis of the plug; a gland in threaded engagement with the threaded portion aforesaid of said shell and which gland has an end portion of reduced size so arranged 100 relative to said follower as to contact with the upper surface thereof about midway the width thereof and throughout an annular band or zone of small width as compared with the width of said follower; and a 105 gasket interposed between the ledge aforesaid and the lower of the shoulders of said insulator.
6. In a spark plug of the class described, a hollow metallic shell or casing having a 110 threaded portion adjacent its upper end, and an internal annular ledge located below said threaded portion; an insulator secured in place within said shell and having a lower annular shoulder adapted to overlie said ledge, and an upper shoulder; an annular metallic follower located within said shell and above the upper of the shoulders of said insulator; a gland nut in threaded engagement with the threaded portion aforesaid of 115 said shell, and the lower end of which gland is in engagement with the upper surface of said follower throughout an annular zone of small width as compared with the width of said upper surface; and a yieldable gasket 120 interposed between the ledge aforesaid and the lower of the shoulders upon said insulator. 125

In testimony whereof I affix my signature.
ALBERT CHAMPION.
